UNITED STATES PATENT OFFICE.

HUTCHINSON L. BEVIER, OF DULUTH, MINNESOTA.

ARCHER'S BOW.

Application filed June 8, 1925. Serial No. 35,689.

My invention relates to archers' bows, and has for its object the provision of an improved bow of the type referred to. My invention consists of the structures, combinations and arrangements of parts hereinafter described and claimed.

In the drawings, Fig. 1, is a side elevation of one form of my said invention. Fig. 2 is an enlarged fragmentary central, vertical, 10 longitudinal section through said Fig. 1 omitting the hereinafter described winding. Fig. 3, is a top plan view of the fragment shown in Fig. 2. Fig. 4, is a fragmentary side elevation of a modified form of said bow. Fig. 5, is a central, vertical, longitudinal section through a second modified form of my said invention, and Fig. 6, is a reduced top plan view of the fragment shown in Fig. 5.

In the drawings, 1 is a primary bow-leaf of wood extending the full length of the completed bow. Centrally positioned elongated face plates 2 and 3 are secured to the upper and lower faces of said leaf, respectively, by any suitable means, as by clinched nails 4. Secured to said primary leaf is a shorter secondary leaf 5, preferably of steel, the axes of which leaves are approximately in the same planes. Said secondary leaf is 20 rigidly secured for a short distance each side of its center to said primary leaf by any suitable means, as by any suitable binding 6, or by said nails, or both binding and nails, but is free at its ends to slip longitudinally 30 with respect to said primary leaf. In said modified form (Fig. 4) a third and shorter leaf 7 is incorporated in said bow in similar manner to the incorporation of said secondary leaf therein. In broad bows, said leaves 40 and plates 2 and 3 preferably have an elongated central sighting aperture 8 which may, if desired, be made large enough to also form a passage for the shaft of an arrow. Said aperture may be of any suitable or desired contour.

Before securing the plates 2 and 3, the primary leaf is preferably bent a little each side of the center, and said plates are secured so as to aid in holding the center in the desired form. In the event that said 50 aperture 8 is provided, said binding 6 is preferably wound through said aperture around the opposite sides thereof without crossing said aperture, but may be extended across the plates beyond the ends of said 55 aperture.

If desired, a guide thimble 9 may be extended upwardly or downwardly at right angles to the centers of the bow leaves, which thimble is adapted to receive and 60 form a guide for the arrow, substantially as shown in Figs. 5 and 6.

What I claim is:

1. In an archer's bow the combination with a bow leaf of upper and lower face 65 plates secured thereto, said plates and bow leaf having a sighting aperture formed therein.

2. In an archer's bow, the combination with a primary bow leaf of a shorter secondary bow leaf secured thereto intermediate of its ends, said leaves having a sighting aperture extending therethrough.

3. In an archer's bow, the combination of a plurality of resilient leaves, a centrally 75 disposed plate for holding said leaves in rigid position for a short distance on each side of their centers, said leaves and plate having a sighting aperture extending therethrough.

4. In an archer's bow, the combination of a plurality of resilient leaves, and a centrally positioned transversely directed thimble adapted to receive and form a guide 85 for the shaft of an arrow.

In testimony whereof, I hereunto affix my signature.

HUTCHINSON L. BEVIER.
